CLAIM

The ornamental design for a bench, as shown and described.

DESCRIPTION

FIG. 1 is a right, front perspective view of the bench showing my new design;

FIG. 2 is a front elevational view of the bench of FIG. 1, the rear view being a mirror image thereof;

FIG. 3 is a right-side elevational view of the bench of FIG. 1; and,

FIG. 4 is a left-side elevational view of the bench of FIG. 1.
